[57] CLAIM

The ornamental design for a faucet body, as shown and described.

DESCRIPTION

FIG. 1 is a perspective view of a faucet body taken from the top front showing our new design;

FIG. 2 is a perspective view thereof taken from the top rear;

FIG. 3 is a front elevational view thereof;

FIG. 4 is a top plan view thereof;

FIG. 5 is a left side elevational view thereof, the right side being a mirror image of the left side;

FIG. 6 is a rear elevational view thereof; and,

FIG. 7 is a bottom plan view thereof.

The broken line representation of the handle and aerator in FIG. 1 is for purposes of illustration only and forms no part of the claimed design.

1 Claim, 4 Drawing Sheets
